FOREIGN PATENT DOCUMENTS

CN 201240577 Y 5/2009

Primary Examiner — Dana Meyrow(74) *Attorney, Agent, or Firm* — Adibi IP Group, PC; Amir V. Adibi; Andrew C. Palmer(57) **CLAIM**

The ornamental design for a bottle with cap holder, as shown and described.

DESCRIPTION

FIG. 1 is a bottom perspective view of a bottle with cap holder showing my new design, shown with the cap applied to the holder;

FIG. 2 is a bottom perspective view thereof, with the bottle shown in the closed position;

FIG. 3 is a left side elevation view of the configuration shown in FIG. 1;

FIG. 4 is a right side elevation view thereof;

FIG. 5 is a front elevation view thereof;

FIG. 6 is a rear elevation view thereof;

FIG. 7 is a top plan view thereof; and,

FIG. 8 is a bottom plan view thereof.

The broken lines in the drawings illustrate the portions of the bottle with cap holder that form no part of the claimed design.

1 Claim, 4 Drawing Sheets(56)
